UNITED STATES PATENT OFFICE

EARL C. STAUFFER, OF LANCASTER, PENNSYLVANIA

DOMESTIC BOILER

Application filed March 30, 1931. Serial No. 526,473.

The present invention relates to boilers of the domestic heating type, and method of operation thereof, and consists in the combinations and arrangements of elements of apparatus, and function or operation thereof, as hereinafter described and particularly set forth in the accompanying claims.

In ordinary domestic boilers where the combustion chamber or fire place is located below the water body both the water travel and course of products of combustion are upwardly, and also there is internal water circulation in the boiler proper which creates considerable resistance to the flow of hot water to the radiators of the heating system. These conditions are due to the fact that the heated water or lower strata thereof must move upwardly and displace cold water at the top and this condition obtains until the temperature of the whole water body has become substantially uniform or high enough to cause circulation through the system, and consequently considerable time is lost in bringing the heating system to proper temperature.

A further defect in this operation of up-draft fired boilers is that in their upward travel the heated gases or products of combustion do not have sufficient or long enough contact with the boiler surfaces, or stated in another way, the heated gases pass up too quickly and out of the furnace and thereby do not give that rubbing or contact effect against the boiler surfaces which they must necessarily do for maximum recovery of heat from fuel consumed. All the foregoing obviously operates to lessened efficiency and needlessly high cost of operation.

To overcome these disadvantages the present purpose is to provide a top-fired and down-draft type of boiler which is characterized in having the heating flame at the top of the boiler where, acting on a relatively thin water film, steam or hot water will be quickly generated and caused to promptly travel through the water pipe of the heating system in a relatively short time after starting the fire. Furthermore, by having the heat at its highest temperature applied at the top of the boiler and the lowest temperature

of the heat at the bottom the boiler operator to create a more efficient and rapid rate of heat transfer. Thus the downward course of heating gases being counted to the direction of normal travel (i. e. upwardly) said gases are crowded or packed against the side walls of the boiler.

The invention further contemplates constructing a boiler of this type having a bypass exhaust or smoke box permitting any unburned or unignited gases to not accumulate sufficiently long to permit of proper mixture for combustion in the event of ignition failure. Another object of the invention is to equip the boiler with an auxiliary or independent unit to heat water for domestic consumption and in having an incinerator self-contained within the boiler structure and efficiently operated thereby. That is to say, the incinerator here proposed has its own heating unit supplied entirely through the heat of the boiler proper.

The invention is shown by way of illustration in the accompanying drawings, wherein:

Figure 1 is a perspective view of the boiler complete.

Figure 2 a similar view showing a slightly modified construction.

Figure 3 a central sectional view of the preferred type of boiler.

Figure 4 a longitudinal sectional view thereof.

Figure 5 a detailed perspective view showing one of the boiler units or sections.

Figure 6 a perspective view of the incinerator unit.

Figure 7 a detailed view in section showing the coupling joint between two boiler units, and;

Figure 8 is a transverse sectional view of a modified type of boiler.

Referring to the construction in further detail, and wherein like reference characters designate corresponding parts in the different figures shown, the boiler consists of a plurality of sections or units 9 preferably of the design shown in Figure 5 and which are assembled back-to-back and secured by suitable couplings 10 having adjustable engagement with the screw-threaded portions 11.

projecting from opposite sides of each section as illustrated in Figures 4, 5 and 7. Each of said units or sections is provided with a plurality of integral flange portions 5 12 and 13 (see Figure 5) which meet in intimate contact with corresponding flanges on the next adjacent sections and thereby provide suitable spaces 14 between the several assembled sections. Said flanges are further 10 designed and located in such relation that they form baffles serving to provide definite channel-ways or passages for circulation of the products of combustion as will be understood.

5 In their assembled relation the sections provide a continuous fuel combustion chamber or fire place 15 extending from the front to the rear of the boiler, and located therein is a gas or oil fuel burner 16 of any approved 15 type substantially co-extensive in length with the fire place. The burner 16 is equipped with a fuel supply pipe 17, having a reducing valve 18, and a pilot light apparatus 19 in the usual way. In the construction 20 shown herein there are four sections assembled though it will be understood, of course, a lesser or greater number may be connected. In either event the whole is formed into a single unitary structure having a suitable asbestos lining 20 as indicated 25 in Figures 3, 7 and 8, and any desired form of sheet metal 21 forms the boiler casing as indicated in Figures 1 and 2.

A flue 22 leading to atmosphere is connected to communicate with the boiler through the pipes or tubes 23 and 24 located respectively at the upper and lower flue fittings 25 and 26 as in Figure 4. A water supply pipe 27 leads to the boiler and a similar 30 pipe 28 has suitable connection with the radiator of the heating system.

It will be noted that the construction and design of boiler unit (Figure 5) is of appreciably lesser width at the bottom than at the 35 top, the purpose whereof being to provide constricted passageways between the several sections and having their decreasing dimensions in the direction of flow of combustion products. That is to say, the spaces between 40 the several sections are relatively more narrow at the bottom than at the top to the end of more efficiently accommodating or allowing 45 for the decrease in volume of the heating gases progressively as they pass from the region of greatest temperature to the region of lesser temperature. By this arrangement 50 a maximum efficiency of the boiler is obtained inasmuch as the tendency to crowding 55 of heating gases as they move downwardly insures their rubbing against and having close and intimate contact with the water surface of the boiler in those regions where the water is coldest, i. e. along the 60 bottom portions thereof. This system furthermore 65 keeps the potential heat flow at

various positions of the boiler at a true balance since the returning hot water of the heating system will enter the boiler at its least active position or coldest part causing a gradual warming up as it travels through 70 the boiler and thereby eliminates the possibility of sudden contraction which frequently causes breakage or cracking in the apparatus of up-draft fired boilers.

By this downward decrease in width of 75 the boiler within the casing there is provided suitable spaces 29 and 30 to either side which are utilized to receive a suitable water heater 31 and an incinerator 32 as shown in Figure 3. The heater 31 is equipped with the usual inlet and outlet water pipes 33 and 34 respectively. The incinerator 32 is provided with a plurality of apertures 35 uniformly spread over the adjacent boiler surface 36 to the end of admitting the maximum of heated gases 80 within the space or chamber 30, and a suitable flue 37 connects with pipe 38 leading to the outlet flue 22 (see Figure 1). An opening 39 gives access to the incinerator through the ash door 40 and a similar material feeding door 41 communicates with the incinerator 85 from the outside.

In the arrangement disclosed in Figure 8 the construction is in all respects the same as that described above excepting that in this instance the boiler units slope from one side as distinct from both sides as in Figure 5. In this arrangement (Figure 8) the space between the boiler units and the casing is utilized to hold the incinerator 32. In all 90 other respects the arrangement and manner of operation of the boiler are the same as that in the Figures 3 and 4.

When in the ordinary boiler an intermittent fire is employed there is considerable heat 95 lost due to cold air passing up or through the boiler when the fire stops. This cold air travels at high velocity through all the passageways through the ordinary boiler absorbing the heat from the internal surfaces. In 100 the construction of boiler disclosed herein there is a direct flue passageway open when the fire is off and consequently cold air does not pass through the entire boiler but only 105 through the relatively small open section at the top thereby reducing the heat lost while the fire is not in operation.

Further advantages in the operation of the 110 boiler are: First, increased velocity due to the constricted passageways between the boiler sections; secondly, the velocity of gases 115 with relation to the water is materially increased due to the counter flow of gas and water.

It is to be understood the invention is not limited to the details of construction here shown and described, but that these may be varied widely without departing from the spirit of the invention as defined by the 120 claims.

What is claimed as new is:

1. In a domestic boiler the combination of a plurality of sections assembled in spaced relation providing combustion passageways therebetween, means restricting the flow of gases to the combustion passageways between the sections each of said sections being of decreasing cross-section downwardly whereby to cause crowding of heating gases as they move downwardly and insure their rubbing against the water surface of the boiler where the water is coldest, and a fuel burner located at the upper portion of the boiler as and for the purpose set forth. 5
2. In a domestic boiler the combination of a plurality of sections, means restricting the flow of gases to the combustion passageways between the sections said sections having contacting flange portions arranged to provide circuitous passages therebetween for combustion gases, said sections being of decreasing cross-section downwardly whereby to cause crowding of heating gases as they move downwardly and insure their rubbing against the water surface of the boiler where the water is coldest, and a fuel burner located at the upper portion of the boiler, as and for the purpose set forth. 10
3. In a domestic boiler the combination of a plurality of sections, means restricting the flow of gases to the combustion passageways between the sections said sections having contacting flange portions arranged to provide circuitous passages therebetween for combustion gases, a fuel burner located at the upper portion of the boiler, and all of said sections being of decreasing cross-section downwardly whereby to cause crowding of heating gases as they move downwardly and insure their rubbing against the water surface of the boiler where the water is coldest, as and for the purpose set forth. 15
4. In a top-fired down-draft boiler the combination of a plurality of sections assembled in spaced relation and having registering openings providing a fuel burning chamber adjacent the top of the boiler, means restricting the flow of gases to the combustion passageways between the sections, a fuel burner in said chamber, and said boiler sections being of decreasing cross-section downwardly whereby to cause crowding of heating gases as they move downwardly and insure their rubbing against the water surface of the boiler where the water is coldest, as and for the purpose set forth. 20
5. In a top-fired down-draft boiler the combination of a plurality of sections assembled in spaced relation and having registering openings providing a fuel burning chamber adjacent the top of the boiler, a fuel burner in said chamber, means restricting the flow of gases to the combustion passageways between the sections flanges formed on opposite sides of the sections providing circuitous passages for combustion gases between the respective sections, and said boiler sections being of decreasing cross-section downwardly whereby to cause crowding of heating gases as they move downwardly and insure their rubbing against the water surface of the boiler where the water is coldest, as and for the purpose set forth. 25
6. In a top-fired down-draft boiler the combination of a plurality of sections assembled in spaced relation and having registering openings providing a fuel burning chamber adjacent the top of the boiler, a fuel burner in said chamber, an inclosing casing for the boiler, said sections being of decreasing width downwardly whereby to cause crowding of heating gases as they move downwardly and insure their rubbing against the water surface of the boiler where the water is coldest, the lower ends of said sections also providing a space within the casing, and an auxiliary heating apparatus located in said space, substantially as set forth. 30
7. In a top-fired down-draft boiler the combination of a plurality of sections assembled in spaced relation and having registering openings providing a fuel burning chamber adjacent the top of the boiler, a fuel burner in said chamber, an inclosing casing for the boiler, said sections being of decreasing width downwardly whereby to cause crowding of heating gases as they move downwardly and insure their rubbing against the water surface of the boiler where the water is coldest, the lower ends of said sections also providing spaces to either side within the casing, and an auxiliary heating apparatus located in each of said spaces respectively, substantially as set forth. 35
8. In a top-fired down-draft boiler the combination of a plurality of sections assembled in spaced relation and having registering openings providing a fuel burning chamber adjacent the top of the boiler, a fuel burner in said chamber, an inclosing casing for the boiler, said sections being of decreasing width downwardly providing spaces to either side of the sections within the casing, and an auxiliary water heater and an incinerator located in said spaces respectively, substantially as set forth. 40
9. A section for a top-fired down-draft boiler comprising a unitary casting constructed of decreasing cross-section downwardly said section adapted to be contained in a closely fitting casing whereby to cause crowding of heating gases as they move downwardly and insure their rubbing against the water surface of the boiler where the water is coldest, and said casting having an opening adjacent the top thereof to receive a fuel burner, as and for the purpose set forth. 45
10. A section for a top-fired down-draft boiler comprising a unitary casting constructed of decreasing cross-section downwardly 50

said section adapted to be contained in a closely fitting casing whereby to cause crowding of heating gases as they move downwardly and insure their rubbing against the water surface of the boiler where the water is coldest, and said casting having an opening adjacent the top thereof to receive a fuel burner, flanges formed on opposite sides of the casting providing circuitous passageways for combustion gases when the sections are assembled, as and for the purpose set forth.

11. In a top-fired down-draft boiler the combination of a plurality of sections assembled in spaced relation and having registering openings providing a fuel burning chamber adjacent the top of the boiler, a fuel burner in said chamber, a casing for the boiler, said sections being of decreasing area downwardly providing a space on one side within said casing, and an incinerator located in said space, said incinerator having openings formed in the side thereof immediately adjacent the surface of the sections, as and for the purpose set forth.

12. A section for a top-fired down-draft boiler having an opening adjacent the top thereof to receive a fuel burner, a projecting flange along the bottom and side edges of said opening adapted to cause the products of combustion to pass upwardly from the burner chamber when the sections are assembled as and for the purpose set forth.

13. A section for a top-fired down-draft boiler having an opening adjacent the top thereof, said openings providing a fuel burning chamber when the sections are assembled; laterally projecting flanges along the bottom and side edges of said openings adapted to contact with corresponding flanges on adjacent sections when the sections are assembled thereby causing the products of combustion to pass upwardly from the chamber and thence downwardly between the sections as and for the purpose set forth.

14. In testimony whereof I affix my signature.
EARL C. STAUFFER.
